Primary Examiner — W. A. Teddy Falloway*Assistant Examiner* — Sarah J Ault(74) Attorney, Agent, or Firm — BRENT WHITLOCK LAW, LLC; Brent K. Whitlock(57) CLAIM

The ornamental design for a key emblem, as shown and described.

DESCRIPTION

FIG. 1 is a perspective view of a key emblem showing my new design;

FIG. 2 is a right-side elevation view thereof;

FIG. 3 is a left-side elevation view thereof;

FIG. 4 is a rear view thereof;

FIG. 5 is a front view thereof;

FIG. 6 is a top plan view thereof; and,

FIG. 7 is a bottom plan view thereof.

The broken lines depict environmental structure and form no part of the claimed design.

1 Claim, 5 Drawing Sheets(56)
